ELECTRICAL FUSE TONGS.

APPLICATION FILED JAN. 8, 1910.

981,857.

Patented Jan. 17, 1911.

UNITED STATES PATENT OFFICE.

ALBERT M. HUBBARD AND CHARLES H. CAUSEY, OF ST. ANTHONY, IDAHO.

ELECTRICAL-FUSE TONGS.

981,857.

Specification of Letters Patent. Patented Jan. 17, 1911.

Application filed January 3, 1910. Serial No. 536,984.

To all whom it may concern:

Be it known that we, ALBERT M. HUBBARD and CHARLES H. CAUSEY, citizens of the United States, and residents of St. 5 Anthony, in the county of Fremont and State of Idaho, have invented an Improvement in Electrical-Fuse Tongs, of which the following is a specification.

Our invention is an improved insulated 10 tongs or hand-gripper for holding and handling electrical fuses or other electrical devices with safety.

The invention is embodied in the combination and arrangement of parts as herein 15 described, and illustrated in the accompanying drawings, in which:—

Figure 1 is a side or plan view of the tongs. Fig. 2 is a side or edge view of the lower portion of the tongs, the view being at 20 right angles to that shown in Fig. 1. Fig. 3 is a longitudinal section of the main portion of the tongs. Fig. 4 includes a face and edge view of the recessed cam forming a part of the instrument. Fig. 5 is a side 25 view of the steel shank or block to which the cam is secured.

The fuse-grippers 1, 1, are formed of wood and attached to jaws 2 by means of wooden pins 3 which are secured detachably by cot- 30 ter-pins 4. The jaws 2 are pivoted at 5 in the metal casing 6, and a cam 7 is arranged between their inner ends at the top of the casing. The latter is provided with a side opening having a detachable closing plate 35 6^a which is attached to the body or main portion 6 by screws.

A tube 13 is secured to the body 6, and a handle portion 15 is fixed thereon. A tube 12 is arranged within the tube 13, and on its 40 outer end a handle portion 14 is secured. The outer tube 13 is permanently connected with the body 6. In order to connect the double cam to the inner tube 12 so that it can be rotated therewith, I provide the following attachment. A cylindrical block 9— 45 see Fig. 5—is secured in the inner end of the tube 13 by means of cross pins 11, and the lower end of the block is provided with a

squared portion from which a smaller cylindrical threaded portion projects. When 50 the body of the block has been secured in the inner tube 12, such squared and threaded portion projects therefrom.

The cam 7 is provided with a squared hole 55 adapted to receive the squared portion of the block 9, and a nut 10 is screwed on the threaded portion. Obviously, however, this cannot be done until after the tube 12 shall have been inserted in the outer tube 13, and the operation is effected through the opening 60 in the side of the casing. In other words, the cam is inserted through the opening and slipped on the squared portion of the block 9, and then the nut is applied and screwed on the threaded portion. Thus, the tube 12 65 is held rotatively in the outer tube 13. It is obvious that by seizing the handle portion 15 with one hand and the outer portion 14 of the handle with the other hand, the cam may be rotated as required to open and close the 70 jaws.

A spiral spring 18 is arranged between the 75 jaws, below their pivots, and serves to hold their upper ends or shanks engaged with the cam.

What we claim is:—

The fuse-tongs herein described, comprising pivoted jaws, a casing having a lateral opening, a tube permanently connected with said casing and having a handle portion secured thereto, a smaller tube inserted in the first-named tube and having an outer handle portion by which it may be rotated, a cylindrical block fixed in the lower end of the inner tube and having a squared and threaded portion projecting therefrom, a double cam having an opening to receive the squared portion of the block, and a nut adapted to screw on the threaded portion, such cam and nut being insertible through the side opening of the casing, as shown and described. 85 90 95

ALBERT M. HUBBARD.
CHARLES H. CAUSEY.
